UNITED STATES PATENT OFFICE.

WILLIAM R. ROGERS, OF NEWARK, NEW JERSEY, ASSIGNOR TO WILLIAM RAUBITSCHICK, OF NEW YORK, N. Y.

SEWING-MACHINE.

1,239,825.

Specification of Letters Patent. Patented Sept. 11, 1917.

Application filed June 30, 1915. Serial No. 37,233.

To all whom it may concern:

Be it known that I, WILLIAM R. ROGERS, a citizen of the United States, and a resident of Newark, in the county of Essex and State 5 of New Jersey, have invented a new and Improved Sewing-Machine, of which the following is a specification.

My invention is directed more particularly to providing a sewing machine, which 10 produces zig-zag stitches, with mechanism adapted, among other things, for the production, by automatic means, of a straight seam with gaps, to unite a strip of fabric material of indeterminate length, to a body, 15 or base, fabric, on which it is mounted and supported, while producing gaps therein, as hereinafter described.

I am aware that it is not new to produce mechanically, a single gap of determinate 20 width, in such a seam, but such gap is thus produced by so changing the operative position of the material, that it shall be sufficiently out of alignment with the seam, that the needle shall not engage the material of 25 the strip, but only the body fabric during the interval required to produce such gap, thus leaving a gap of determinate width adapted for the side opening in a stay pocket, but the same is not produced by automatic means 30 nor is the mechanism adapted for such automatic production thereof at measured intervals, or for the reinforcement of the seam 35 by a continuous series of automatic operations, with a plurality of tie stitches at the beginning and end of each gap.

Among other objects, my invention includes that of providing automatic means for the mechanical stitching of a seam of the character described, which shall be adapted 40 to produce a fabric structure suitable for mounting thereon, in operative position, of a set of hooks and eyes, by engaging the mates of the pairs in the gaps thus provided, they being retained in such position 45 by their shanks, thus dispensing with the necessity for stapling the hooks and eyes to the fabric, thus obviating the objectionable features of such method.

A practical embodiment of the invention 50 is represented in the accompanying drawings forming a part of this specification, in which similar characters of reference indicate corresponding parts in all the views.

Figure 1 is a side elevation of the sewing

machine with parts shown in section and 55 with the guides for the fabric strips omitted;

Fig. 2 is an elevation of the front end of the same with the guides for the fabric strips in position;

Fig. 3 is an enlarged transverse section of 60 the sewing machine on the line 3—3 of Fig. 1;

Fig. 4 is a similar view of the mechanism for imparting lateral reciprocatory motion to the feed bar while it is inoperative; 65

Fig. 5 is a sectional plan view of the same on the line 5—5 of Fig. 3 and with the parts in operative position;

Fig. 6 is a plan view of two fabric strips sewed together to form spaced openings for 70 hooks or eyes; and

Fig. 7 is an enlarged transverse section of the same on the line 7—7 of Fig. 6.

In sewing machines of the class mentioned as adapted to produce a zig-zag stitch, the 75 means now in use for producing such stitches includes one type which provides a positive, lateral reciprocatory motion of the needle bar between vertical reciprocations of the latter, the same being mounted to reciprocate vertically both in its normal and deflected positions, and another type in which the needle bar is fulcrumed to vibrate laterally, and to normally reciprocate vertically, but at an angle in the deflected position. 80 85

In the drawings I show my invention as embodied in a sewing machine of the Singer, vibratory needle type; it is however, manifest that my automatic mechanism for the 90 control of the lateral motions of the needle bar is equally adapted for the control of a needle bar mounted to reciprocate vertically in both positions, without departing from the spirit of my invention; and that 95 this phase of construction is not material as affecting its utility, or scope.

The stitch-producing mechanism of the sewing machine consists of a needle A and the usual looping device B, of which the 100 needle A is secured in a needle bar C mounted to reciprocate in an arm D fulcrumed at its upper end on the bracket arm E of the sewing machine. By the arrangement described the arm D and the needle bar C 105 and with it the needle A can be vibrated laterally, that is, from a normal vertical position to right and back again to vertical

position. The needle bar C is connected by the pitman F and crank F' with the needle bar shaft F² for imparting a continuous reciprocating motion to the needle bar C and the needle A.

The automatic mechanism for controlling the lateral motions of the needle bar is as follows: A transverse cam shaft G is journaled in suitable bearings arranged on the bracket arm E and on the said cam shaft G is secured a worm wheel G' in mesh with a worm G² secured on the needle bar shaft F² so that when the latter is running a rotary motion is given to the shaft G to rotate the latter in the direction of the arrow a'. On the front end of the shaft G is secured a cam H in the form of a wheel having in its peripheral face two sets of diametrically opposite notches or recesses H', H² and H³, of which the notches H' and H³ are comparatively short in comparison with the notches H², as will be readily understood by reference to Fig. 1. The peripheral face of the cam H is engaged by a friction roller I journaled on the free end of an arm I' mounted to move laterally on the bracket arm E and pressed on by a spring I² to hold the friction roller I in engagement with the peripheral face of the cam H. The arm I' thus receives lateral motion from the cam H when the roller I engages in any of the recesses in the periphery of the cam and again when the roller is disengaged from the recess and such motion is transmitted by it to the needle bar frame D through the link J'; to the part J² of which it is connected by the pin J let through the slot or guideway J³. By the lateral motions thus imparted the needle bar C is deflected by the entry of the roller into a recess and it is reciprocated in such deflected position until the roller is disengaged from the recess when the needle bar is returned to its normal position. The link J' is preferably made in two parts J², J³ adjustably connected with each other to permit of accurately setting the arm D. For the purpose mentioned, the part J² is provided with an elongated slot J⁴ through which extend screws J⁵ engaging the part J³ to allow of adjusting the latter relatively to the part J². In order to vary the sidewise throw of the needle bar C, the pivot J is adjusted up or down in the guideway I³. When the cam H is rotating in the direction of the arrow a' then the needle bar C is held in vertical position as long as the roller I travels on the peripheral face of the cam H. When the roller I passes into the first notch H' and travels along the same then the needle bar C is swung to the right and is returned to normal position by the roller emerging from the recess and immediately thereafter the friction roller passes into the second notch H² to again cause oscillation of the needle

bar to the right and holding of the needle bar in this position until the friction roller I passes out of the notch H², at which time the needle bar is swung back to vertical position and immediately thereafter the friction roller I passes into the notch H³ to again oscillate the needle bar to the right and to return the needle bar to vertical position at the time the friction roller I passes out of the last notch H³. By the arrangement described, the stitch-producing mechanism makes a row of stitches K while in vertical position to fasten the two strips L and L' together along the side of the edge of the strip L; during the time the friction roller passes in and out of the notch H³, the cross or tie stitches K' are made; during the time the friction roller I travels along the notch H², a row of stitches K² is made on the strip L only; and during the time the friction roller I passes in and out of the notch H³, cross stitches K³ are made from the piece L' onto the piece L, after which the row of stitches K is continued, as will be readily understood by reference to Figs. 6 and 7. Thus by the arrangement described an opening L² is left between the strips L and L', the opening being of a length corresponding to the distance between the cross stitches K' and K³. A hook or eye L³ may be readily projected through the opening L², as indicated in Fig. 6, with the base of the hook or eye L³ abutting against the seam formed by the stitches K uniting the two strips L and L' with each other.

During the time the rows of stitches K and K² are made, the feed bar N is operative, but during the time the cross stitches K' and K³ are made the feed bar N is rendered inoperative. For this purpose the following arrangement is made: The feed bar N is provided with a transversely extending arm N' fulcrumed on an arm O' of a rock shaft O extending lengthwise of the machine underneath the base E' and journaled in suitable bearings attached to the said base. When the shaft O is rocked a forward and backward movement is given to the feed bar N. An up and down swinging movement is given to the feed bar N by the usual mechanism, including a hollow rock shaft P having an arm P' movably engaging a fork N² formed on the feed bar N. The shaft P is provided near its rear end with an arm P² connected by an eccentric rod P³ with an eccentric P⁴ held on the needle bar shaft F² so that when the machine is operated a continuous rocking motion is given to the shaft P which by the arm P' imparts an oscillatory movement to the feed bar N. Through the hollow shaft P extends the shaft B' driving the looping device B and driven by pulleys B², B³ and a belt B⁴ from the needle bar shaft F².

The rock shaft O, previously mentioned, is provided at its rear end with an arm O² provided with an elongated slot or guideway O³ in which is movably mounted a slide Q also 5 engaging a guideway R² in a swing arm R having its pivot R' journaled in a bearing formed on a bracket E² depending from the base E'. The arm R is pivotally connected with an eccentric rod S of an eccentric S² 10 mounted on the needle bar shaft F², so that when the machine is operated the arm R is caused to oscillate and the oscillatory movement of the arm R is transmitted by the slide Q to the arm O² to rock the shaft O. 15 The slide Q is provided with a pivot pin Q' pivotally connected by a link T with one arm of a bell crank lever T' fulcrumed at T² on the under side of the base E' and connected at its other arm by a link U with one 20 arm of a bell crank lever U' fulcrumed on one side of the arm E and carrying at its other arm a friction roller U² engaging a groove V' in the peripheral face of a cam V secured on the shaft G previously mentioned. 25 The cam groove V' is provided with offsets V², V³ for imparting a swinging motion to the bell crank lever U'. During the time the friction roller U² is traveling through the straight portion of the cam V and groove 30 V', the slide Q is held in the guideway of the arm R a distance from the axis of the arm, so that a swinging motion is given by the slide Q to the arm O² to rock the shaft O, as previously mentioned. When, however, 35 the friction roller U² moves into engagement with the offset V² or V³ then a rocking motion is given to the bell crank lever U' whereby a similar rocking movement is given to the bell crank lever T' so that the 40 slide Q is moved into central position relatively to the axis of the pivot R' and consequently the slide Q does not impart a rocking movement to the shaft O for the time being. The offsets V² and V³ are so arranged 45 relatively to the notches H', H³ that when the cross stitches K' and K³ are made the forward and backward feeding movement of the feed bar N ceases, but during the time the rows of stitches K and K² are 50 made the friction roller U² travels in the straight portions of the groove V' and the slide R is a distance from the center of the pivot R', and hence a rocking motion is given to the shaft O, thus moving the feed 55 bar N forward and backward.

The link T, previously mentioned, is preferably made in two parts T³, T⁴, adjustable one on the other to lengthen or shorten the link, and for this purpose the part T³ is provided 60 with an elongated slot T⁵ through which extend screws T⁶ screwing in the part T⁴. On loosening the screws T⁶ the part T⁴ of the link T can be adjusted to lengthen or shorten the length in order to obtain proper

adjustment of the pivot pin Q' and the slide 65 Q to move the latter into axial alinement with the pivot R', as previously explained.

The fabric strips L and L' pass through suitable scrolls W, W' attached to the base E' at the front of the machine to double up 70 the edges of the strips and to properly guide the same to the needle A, the feed bar N and the presser foot X of usual construction (see Fig. 2). The strips L and L' prior to reaching the scrolls W and W' pass through 75 tension devices W², W³ and the strips are guided to the said tension devices over a guide rod W⁴.

The operation is as follows:

When the machine is operated, the stitch-producing mechanism forms a row of stitches K for a predetermined distance and then the forward and backward feeding movement of the feed bar N ceases and the needle bar C is oscillated laterally to form the first cross or tie stitches K', that is, at the time the friction roller I passes through the notch H'. When the friction roller I engages in the notch H² the needle bar C is held in deflected position and the short row of stitches K² is 80 now formed on the trip L' only, and during this time the feed bar N is operatively positioned. When the end of the rows of stitches K² is reached, the operative movement of the feed bar N ceases and the needle bar C is again oscillated to form the cross stitches K³, the friction roller I then passing through the notch H³. When the friction roller I leaves the notch H³ the needle bar 85 C is returned to vertical position and is held in this position for forming the next row of stitches K to fasten the strip L to the strip L'. 90

There is a related motion between the 105 needle bar and the feed bar whereby at periodic intervals, during which the feed bar is inoperative, the needle bar is operatively vibrated laterally, between downward reciprocations, to produce tie stitches, and in the 110 intervals between such lateral vibratory periods of the needle bar the feed bar is operatively reciprocated to advance the material forward in a straight line. Thus by the arrangement described the rows of stitches K are of the same predetermined length and the openings L² are formed intermediate the 115 said rows of stitches K, and the opening has its side walls reinforced by the sets of cross stitches K' and K³ so as to securely hold the hook or eye L³ in position in the opening.

Having thus described my invention, I claim as new and desire to secure by Letters Patent:

1. In a sewing machine, the combination 125 of a feed mechanism for feeding the material forward in a straight line, a stitch producing mechanism having a reciprocating needle bar adapted to vibrate laterally of

the line of movement of the material, means for so vibrating the needle bar and means for rendering the feed mechanism inoperative during such lateral movements of the 5 needle bar.

2. In a sewing machine, the combination of a feed mechanism for feeding the material forward in a straight line, a stitch producing mechanism having a reciprocating 10 needle bar, the needle bar and the feed mechanism being laterally movable relatively one to the other and means for rendering the feed mechanism inoperative at intervals in order to permit of the production 15 of a line of stitching having lateral offsets.
3. In a sewing machine, the combination of a feed bar, a stitch producing mechanism having a reciprocating needle bar adapted 20 to vibrate, a revolute cam, means connecting such cam with such feed bar to periodically render the feed bar inoperative, a second revolute cam and a connection between the latter and the needle bar to vibrate the latter at the time the feed bar is inoperative. 25
4. In a sewing machine, the combination of a feed mechanism having a feed bar, a stitch producing mechanism having a reciprocating needle bar adapted to vibrate lat-

erally, a needle bar shaft connected with 30 the needle bar to reciprocate the latter, a cam shaft driven from the needle bar shaft and provided with two cams, a connection between one of such cams and such feed bar to render the latter periodically inoperative 35 and a connection between the other cam and the needle bar to vibrate the latter during the period the feed bar is inoperative.

5. In a sewing machine, the combination of a feed mechanism for feeding the material in a straight line, a stitch producing mechanism having a reciprocating needle bar, mounted to move laterally of the line of movement of the material, means for moving the needle laterally and operatively 40 retaining it in this position for a predetermined length of time and then returning it to its normal position and means for rendering the feed mechanism inoperative during the lateral movements of the needle bar. 50

In testimony whereof I have signed my name to this specification in the presence of two subscribing witnesses.

WILLIAM R. ROGERS.
